UNITED STATES PATENT OFFICE.

DANIEL B. LUTEN, OF INDIANAPOLIS, INDIANA.

BRIDGE.

1,186,110.

Specification of Letters Patent.

Patented June 6, 1916.

Original application filed November 1, 1906, Serial No. 341,605. Divided and application filed March 29, 1909, Serial No. 486,645. Divided and this application filed July 26, 1911. Serial No. 640,711.

To all whom it may concern:

Be it known that I, DANIEL B. LUTEN, a citizen of the United States, residing at Indianapolis, in the county of Marion and State 5 of Indiana, have invented a new and useful Improvement in Bridges, of which the following is a specification.

My invention relates to improvements in concrete bridges and has for its purpose 10 to provide a structure having joints between the work of different days at points such that they will not injuriously affect the strength or appearance of the structure; and to provide such improvements in details and 15 methods of construction as shall hereinafter be pointed out.

This application is a division of an application filed by me March 29, 1909, Serial No. 486,645, which is a division of an application filed by me November 1, 1906, Serial No. 341,605.

The invention is illustrated in the accompanying drawings in which the same reference characters describe like parts through 25 out the several views.

Figure 1 is a longitudinal section of a concrete bridge; and Fig. 2 is a transverse section illustrating my improvement.

The abutments 20 and piers 21 are built 30 to the springing lines *s* and centering is then erected for one of the arches at the middle of the axis thereof, the centering being wide enough to support a ring of reasonable width. The concrete is laid upon this centering forming a ring *R*. Additional arch rings *R'* may then be produced in the same manner and allowed to set, the operation being repeated as many times as may be necessary to complete the span to a point close to 40 the spandrel wall.

The end rings of the arch and spandrel walls are then formed together, thus bringing the joint 22 in the intrados of the arch instead of in the end face of the structure.

45 The usual construction has hitherto been to build the arch rings complete and then place the spandrel walls upon the arch ring, resulting in an unsightly joint along the extrados of the arch in the face of the wall.

50 It is almost impossible to prevent such a joint from showing a ragged appearance, and seepage from the earth fill penetrates through it thus discoloring the face of the arch. These objectionable features are 55 eliminated by my improved method which

places the joint between the spandrel and the main portion of the arch ring, in the intrados of the arch where it is barely visible. By this means the joints in the arch are made parallel to the lines of thrust, the arch proper being divided into longitudinal rings as by vertical planes parallel to the central line of the roadway. The spandrels or side walls are monolithic with the extreme rings, joints occurring only between 60 this extreme ring and its neighbor and at the expansion joints, which may be of any usual form, as simply a vertical plane joint transverse to the wall near the ends of the span. Thus the entire arch may be divided 65 into rings and sections such that each one may be concreted continuously during a working day, and the construction discontinued at night at the joints as indicated. 70

I claim:—

1. That improvement in the art of building a concrete arch supporting a spandrel wall, comprising erecting the arch in longitudinal sections, and concreting the spandrel wall monolithically with its supporting arch section, one arch section being allowed to harden before construction of the other. 75

2. That improvement in the art of building an arch comprising building a longitudinal section of the arch, allowing the same to harden, and then facing the same with a longitudinal arch section supporting a spandrel integral therewith. 80

3. The improvement in the art of building a concrete arch supporting a spandrel wall, comprising erecting the arch in monolithic longitudinal sections, and concreting the spandrel wall monolithically with the arch section supporting it, one arch section 85 being allowed to harden before the construction of an adjacent section. 90

4. The improvement in the art of building a concrete arch, comprising building monolithically a longitudinal section of the arch, allowing the same to harden, and then facing the same with a monolithic section supporting a spandrel monolithically integral therewith. 100

5. That improvement in the art of building a concrete arch, comprising erecting monolithically a longitudinal section of the arch, allowing it to harden, then erecting monolithically one or more longitudinal arch sections at each side of the hardened 105 110

arch section, and forming a spandrel wall monolithically with the last section so erected at each side.

6. That improvement in the art of building a concrete arch, comprising erecting a longitudinal section of the arch, allowing it to harden, then erecting one or more longitudinal arch sections at each side of the hardened arch section, erecting a spandrel

10 wall on the last section at each side, and

forming such last section and the spandrel wall supported thereby as a monolith.

In witness whereof I, have hereunto set my hand and seal at Indianapolis, Indiana, this 20th day of July, A. D. one thousand 15 nine hundred and eleven.

DANIEL B. LUTEN. [L.S.]
